UNITED STATES PATENT OFFICE.

LEO A. KELLY, OF HOUSTON, TEXAS.

PRINTING-CASE.

1,387,007.

Specification of Letters Patent.

Patented Aug. 9, 1921.

Application filed September 25, 1920. Serial No. 412,645.

To all whom it may concern:

Be it known that 1, LEO A. KELLY, a citizen of the United States, residing at Houston, in the county of Harris and State of 5 Texas, have invented certain new and useful Improvements in Printing-Cases, of which the following is a specification.

This invention relates to new and useful improvements in a printing case, and has 10 been specially designed for the purpose of containing a camera and other apparatus and appliances to be used in printing pictures.

One object of the invention is to provide 15 a case of the character described which may be compactly folded together so as to be easily carried about by tourists and which is arranged to contain a camera and all necessary picture printing supplies and apparatus, and is so designed that it may be readily 20 opened, and arranged in position to be used in the process of printing the pictures taken.

With the above and other objects in view 25 the invention has particular relation to certain novel features of construction, arrangement of parts and use, an example of which is given in this specification and illustrated in the accompanying drawings, wherein:—

Figure 1 is a perspective view of the case closed.

Fig. 2 is a perspective view showing the top or cover in open position.

Fig. 3 is a perspective view showing the case opened and in position to be used for printing.

Fig. 4 shows a perspective sectional view of the case showing an inner cabinet which is hinged thereto.

Fig. 5 shows a perspective sectional view of the case, showing the printing frames employed, and

Fig. 6 shows a perspective view of the cover for the printing frame.

Referring now more particularly to the drawings, wherein like numerals of reference designate similar parts in each of the figures, the numeral 1 refers to the bottom section of the case which is box-like in form, and the numeral 2 designates the cover therefor which is hinged thereto and is also of a 45 box-like contour. This cover has four compartments of a form to receive the metallic pans 3, as shown in Fig. 3, one to contain water, one for a developing solution, one for a fixing bath and an extra pan for miscellaneous use. This cover is normally closed by 50 means of a sectional lid 4 which is held in

closed position by the ordinary hook and eye arrangement 5. When the case is used for printing the cover 4 forms, in effect, a supporting leg therefor, as shown in Fig. 3. 60 This cover has a deep oblong recess 6 in which there is an electrical socket 7 designed to receive the globe 8 which may be folded down into the recess 6, when the case is to be closed. The recess 6 should be lined with asbestos to protect the same from the heat of the light globe 8. This globe is used only when printing in a dark room and usually emits a weak red light so as not to affect the paper. The socket 7 is connected to the electric wiring 9 which is arranged to be attached to a suitable drop cord or other source of supply. Within one end of the section 1 there is hinged a suitable cabinet 10 provided with the drawers 11, 11, provided to 65 contain printing paper, films and plates, and is also provided with suitable pigeon holes 12 designed to contain developing solution, hypo, stirring rod, measuring glass, etc. This cabinet is closed by the cover 13 which is 70 hinged to the bottom thereof and whose free edge carries the hook 14 designed to engage with the eye 15 to hold the cover closed. The bottom section 1 of the case has a transverse 75 partition 16 providing on one side thereof the space 17 within which the cabinet fits when the case is closed. When the cabinet 10 is raised into working position, the cover 13 is brought to a horizontal position with its free edge resting upon the partition 16, thus 80 forming, in effect, a working table. In some cases the proportions will be such that the cover 13 will have to be made in sections, 85 hinged together; as shown in Fig. 3, and in such case, the free edged section may be 90 folded back to lie flat on the other section forming, in effect, a working table. On the other side of the partition 16 there are two compartments separated by a partition 18, one compartment is provided to contain the 95 camera 19 and the other compartment is equipped with red and white electric light globes 20 and 21 which are connected to the wiring 9 and the walls of this compartment are lined with asbestos so as not to be injured by the heat. Above these light globes 100 there is a printing frame 22 provided with a removable cover 23. The film and printing paper are fastened in said printing frame in the usual way, the red light 20 being provided for use by the photographer in the preliminary work of printing. The white light 105 110

is then turned on, a push button 24 being provided for this purpose. The frame may be adjusted to the proper distance to the light by means of the usual folding supports 25, 5 25, of well known construction. When the picture has been printed it is then taken from the frame and subjected to the required solutions for developing and fixing the same, said solutions having been previously prepared in the pans 3.

When the work has been completed, the solutions are removed from their respective pans and the globe 8 folded down into the recess 6 and the electrical conductor 9 may 15 be deposited in one of the pans 3 and the case then closed, thus forming a compact and convenient case for containing all of the essentials, apparatus and appliances for printing pictures.

20 What I claim is:—

1. A case of the character described, including a box-like section having a transverse partition, a cabinet hinged to the case and arranged to fit into the compartment on one 25 side of the partition, said cabinet being movable into vertical position, a cover for said cabinet hinged thereto and arranged to be opened and closed, and when in open position, resting on said partition and forming 30 a table.

2. A case of the character described, including a box-like section having a transverse partition, a cabinet hinged to the case and arranged to fit into the compartment on one 35 side of the partition, said cabinet being movable into vertical position, a cover for said cabinet hinged thereto and arranged to be opened and closed, and when in open position, resting on said partition and forming 40 a table, a lengthwise partition on the other side of said transverse partition and extending therefrom to the end of the case and forming two compartments, one for a camera and the other for a printing frame.

45 3. A case of the character described, including a box-like section having a transverse partition, a cabinet hinged to the case

and arranged to fit into the compartment on one side of the partition, said cabinet being movable into vertical position, a cover for 50 said cabinet hinged thereto and arranged to be opened and closed, and when in open position, resting on said partition and forming a table, a lengthwise partition on the other side of said transverse partition and 55 extending therefrom to the end of the case and forming two compartments, one for a camera and the other for a printing frame, and a cover hinged to said section.

4. A case of the character described, including a box-like bottom section having a transverse partition, a cabinet hinged to the case and arranged to fit into the compartment on one side of said partition, a lengthwise partition leading from the other side 65 of said transverse partition to the end of the case and forming two compartments, one of which is designed to receive a camera and a printing frame in the other of said compartments, a top section, box-like in 70 form, hinged to and adapted to fit into said bottom section, a plurality of pans contained within said top section and a cover hinged thereto and adapted to inclose said pans therein.

5. A case of the character described, including a bottom section, box-like in form and provided with a plurality of compartments, a cabinet fitted into one of said compartments and hinged to the case and arranged to be lifted into vertical position, a cover hinged to the cabinet and when in open position forming a table, a top section 80 hinged to the bottom section, a cover hinged thereto and adapted to form a support therefor when in open position.

In testimony whereof I have signed my name to this specification in the presence of two subscribing witnesses.

LEO A. KELLY.
